The ornamental design for a bead holding board, as shown and described.

DESCRIPTION

FIG. 1 is a top elevational view of a bead holding board showing our new design;

FIG. 2 is a right side elevational view thereof;

FIG. 3 is a front view thereof;

FIG. 4 is a bottom view thereof; and,

FIG. 5 is a cross-section view of FIG. 1 taken along section line 6—6. The left side elevational view would be the same as FIG. 2 and the rear view would be the same as FIG. 3.
